Application March 17, 1937, Serial No. 131,488
In Switzerland March 30, 1936

4 Claims. (Cl. 280—11.13)

The present invention relates to skis and has as its object the provision of particularly shaped retaining teeth on the sliding sole of the ski to prevent backwards sliding of the ski on a slope but which do not interfere with the forward movement of the ski.

According to the invention the teeth are obtained by providing in the sole surface series of recesses extending in directions which are inclined relative to the longitudinal axis of the ski, and one series of recesses being oppositely inclined relative to another series, so that the recesses of two series intersect each other once at least on one half of the width of the ski sole.

15 The accompanying drawing represents by way of example various forms of embodiment of the subject of the invention.

Figure 1 is a fragmentary view of the first form in plane from below; Figure 2 is a section along the line 2—2, and Figure 3 is a section along the line 3—3 of Fig. 1.

Fig. 4 is a view of the second form in plan from below; Fig. 5 is a section along the line 5—5 of Fig. 4.

25 Fig. 6 is a similar plan view of a third form; Figures 7 and 8 are sections along the lines 7—7 and 8—8, respectively, of Fig. 6, drawn to a greater scale.

Fig. 9 is a plan view of a fourth form of embodiment.

The ski according to Fig. 1 comprises a body 1 of wood to which is secured a layer 2 forming the sole of the ski and consisting of a material which is harder than wood and to which the snow does not stick, such as for example celluloid. The sole face of the ski is suitably recessed to provide ratchet teeth 4a and 4b for the purpose of preventing the ski from sliding backwards, and such teeth are cut on both sides of the longitudinal central groove 3 of the sole. Each tooth has an inclined face 5 and a retaining face 6. On each of the two halves of the sole face, separated by the groove 3, are cut two series of teeth which are inclined in opposite directions relative to the longitudinal axis of the ski. The inclined recesses forming the two series of teeth on each half of the sole face meet each other in the middle of each half and thus give the sole face the appearance of a herring-bone gear, one series of herring-bone teeth being provided on each half of the sole face, and the apices of the herring-bone teeth of each series are situated on a longitudinal line extending along the middle of each half of the sole face.

The two branches of the herring-bone teeth form with the longitudinal axis of the ski angles of about fifteen degrees. This angle may vary and may be between ten and forty degrees. The apices of the herring-bone teeth are directed towards the front of the ski and the retaining faces 6 of the teeth are directed towards the back. Owing to the inclination of the teeth relative to the longitudinal direction, the gradient of the front face 5 of the teeth is much smaller 10 in longitudinal section as seen in Fig. 3 than in transverse section as seen in Figure 2. These faces provide only a small resistance against the advancement of the ski. Upon a backward effort the snow is pushed towards the apices of 15 the herring-bone teeth, where it is compressed without being capable of moving away.

In Figures 4 and 5 the cutting depth of the teeth increases from the edge towards the middle of the space comprised between each edge and the groove 3, and a very obtuse angled secondary edge 8 is formed. The face 5 could be convex, or could be separated from the next rearward face 6 by a plane face 11 level with the top of the tooth.

20 In Figures 6 to 8, two series of herring-bone teeth are provided on either side of the groove 3. The height of the holding faces 6 of the teeth is constant from the apice of a herring-bone tooth over the major part of the length of a branch of a herring-bone tooth and then it gradually decreases over the remaining part until the face 6 disappears at a point where there abuts a secondary edge 8a marking the intersection of the lower surface of the sole with the face 5 of the 30 contiguous tooth at the back.

25 The median groove 3 could be omitted and replaced by a fifth row of herring-bone teeth as shown in Figure 11.

The rows of herring-bone teeth are separated 40 from the edges of the ski by portions of smooth surfaces 10 which are not toothed, and are also separated one from the other by such surfaces, in the represented examples. The fact that the edges do not present toothings permits the provision of reinforcement borders of any known type. The toothing of the sole surface can be obtained by pressing, rolling, casting or cutting. I am aware that it has already been proposed to provide the bottom face of skis with a row of 45 retaining teeth to prevent backwards sliding of the ski. But the provision of a single row of parallel teeth has the effect that, when the ski is moving in oblique direction along a slope, a tendency of lateral deviation of the ski is ex- 50 55

perienced. The provision of a row of herring-bone shape teeth on either half of the width of the bottom face removes any such tendency of lateral deviation, because the effect of one series of parallel teeth on the motion of the ski is compensated by the effect of the adjacent series of teeth which are oppositely inclined relative to the longitudinal axis of the ski.

I claim:

10 1. A ski having its lower surface provided with a layer of sliding material, retaining teeth provided in said sliding material for preventing backwards sliding of the ski, said teeth being formed by a plurality of longitudinally arranged series of recesses having the shape of herring-bones, the apices of the herring-bones being situated on a longitudinal line, and the depth of the recesses being constant over a portion of the length of the herring-bones and then gradually decreases over the remaining portion of the length.

25 2. A ski having its lower surface provided with a layer of sliding material, retaining teeth provided in said sliding material for preventing backwards sliding of the ski, said teeth being formed by a plurality of longitudinally arranged series of recesses having the shape of herring-bones, the apices of the herring-bones of each series being situated on a longitudinal line, the branches 30 of the herring-bones forming angles between ten and forty degrees with the longitudinal axis, and the depth of the recesses being constant over a portion of the length of the herring-bones be-

ginning at the apice thereof, and then gradually decreases over the remaining portion of the length.

3. A ski having its lower surface provided with a layer of sliding material, retaining teeth provided in said sliding material for preventing backwards sliding of the ski, said teeth being formed by a plurality of longitudinally arranged series of recesses having the shape of herring-bones, the apices of the herring-bones of each series being situated on a longitudinal line, the branches of the herring-bones forming angles between ten and forty degrees with the longitudinal axis, said sliding surface comprising smooth surface portions separating adjacent series of retaining teeth, and smooth surface portions separating the outermost series of teeth from the lateral edges of the sliding surface.

4. A ski having its lower surface provided with a layer of sliding material, retaining teeth provided in said sliding material for preventing backwards sliding of the ski, said teeth being formed by a plurality of adjacent longitudinal rows of recesses having the shape of herring-bones, the apices of the herring-bones of each row being situated on a longitudinal line, the depth of the recesses decreasing from the apices of the herring-bones towards the outer end of the branches thereof, and said sliding surface comprising smooth surface portions separating the outermost rows of recesses from the lateral edges of the sliding surface.

LOUIS SAHY.
